UNITED STATES PATENT OFFICE

NORMAN CLARK, OF CANTON, OHIO

GYROSCOPIC AND AERODYNAMIC STABILIZER

Application filed July 8, 1929. Serial No. 375,704.

My invention relates to stabilizers for use more particularly with airplanes for increasing their inherent stability and lift.

It is well known that the usual airplane is given a certain degree of inherent stability by the use of a lateral dihedral angle between the main planes and a longitudinal dihedral angle between the center section of the main planes and the stationary portions of the elevator surfaces of the tail.

The operation of such stabilizing means depends on a slight displacement of the airplane towards an unstable position in which position a balancing aerodynamic force is brought into play.

In other words, the usual stabilizing means are aerodynamic in nature, and thus require the presence of air and a time element for their operation.

Under certain conditions, as for example, when the right wing of an airplane suddenly runs into an air pocket, that is to say a region of less pressure than that surrounding the left wing, the difference in pressure between the air surrounding the right and left wings may be of such magnitude as to prevent the automatic operation of the aerodynamic stabilizing means provided by the usual lateral dihedral angle between the right and left wings.

In such a case, if the pilot is not successful in his manipulations of the wing flaps or ailerons, the plane will roll, and may maneuver entirely out of the pilot's control.

The objects of the present improvements include the provision of stabilizing means, which are not entirely of aerodynamic character, and which include mechanical means which may be constantly operated to maintain the plane in the proper position for normal horizontal flight.

Further objects of the improvements include the provision of stabilizing means which are partly aerodynamic in character, and which include aerodynamic means for increasing the lift on the airplane, independently of the lift arising from the reactions of the main wing surfaces.

Further objects of the improvements include the provision of novel means for con-

trolling and varying the operation of the mechanical and aerodynamic elements of the improved stabilizer.

These objects are attained by the improved stabilizer comprising the present invention, which may be described in general terms as including a combined gyroscope and helicopter whose axis of rotation is arranged with respect to the other airplane parts, so that the gyroscopic action of the stabilizer will maintain the airplane in the required position for normal horizontal flight, and the lifting power of the helicopter will increase the lift of the airplane, particularly at the lower flying speeds, and the gyroscope and helicopter means being relatively variable in operation.

A preferred embodiment of the invention is illustrated in the accompanying drawings forming part hereof, in which

Figure 1 is a plan elevation of an airplane equipped with a preferred embodiment of the improved stabilizer hereof;

Fig. 2, a front elevation thereof;

Fig. 3, a side elevation thereof;

Fig. 4, an enlarged fragmentary plan view thereof;

Fig. 5, an axial sectional view thereof as on line 5—5, Fig. 4, the helicopter blade being illustrated in operative position;

Fig. 6, a fragmentary sectional view of the improved stabilizer as on line 6—6, Fig. 5;

Fig. 7, a fragmentary sectional view thereof as on line 7—7, Fig. 6; and

Fig. 8, a fragmentary sectional view thereof as on line 8—8, Fig. 5 illustrating one form of control means for the apparatus.

Similar numerals refer to similar parts throughout the several views.

The improved stabilizer of the present invention indicated generally at 10 may be applied to any type of aircraft, but is here illustrated in use on a monoplane indicated generally at 11.

The improved stabilizer 10 includes a gyroscope wheel 12 preferably including a lower cone 13 having a wide apex angle, and having its apex below its base, and the base terminating in an annular flange 14 of considerable mass for increasing the gyroscopic effect of the stabilizer.

An upper cone 15 also having a wide apex angle preferably equal to the apex angle of the cone 13, and having its apex above its base, is seated at its base in an annular socket 5 16 formed in the base of the lower cone, and the cones are secured to each other at their bases as by screws 17.

The cones 13 and 15 may have their masses decreased between their central hub portions 10 18 and 19, respectively, and the annular flange 14, by forming them with internal hollow conical chambers 20 and 21, respectively.

The lower cone includes radially extending angle walls 22 and 23 merging with walls 15 24 and 25 in the upper cone for forming angled radially extending helicopter slots 26 through the wheel 12.

A movable helicopter cover blade 27 is provided for the upper entrance to each slot, and 20 each blade is connected with the wheel 12 by means of hinges 28 and 28'.

The wheel 12 is provided through the hub portions 18 and 19 with a threaded axial bore 29, which screws upon an upper threaded end 25 of a drive shaft 30.

The drive shaft 30 extends through the center of gravity of the airplane, from a gear connection 31 with an extension 32 of the aircraft engine drive shaft, upwardly 30 through bearings 33 carried in a suitable mounting bracket 34 secured upon the top of the airplane wing 35, and the gyroscope and helicopter wheel are secured as aforesaid on the upper end of the shaft 30.

The shaft 30 is located in the longitudinal plane of symmetry of the airplane, and its angular relation with the longitudinal axis of the airplane is fixed so that when the plane of rotation of the wheel 12 is horizontal, the 40 airplane is in the position for normal horizontal flight.

Thus when the wheel 12 is rotated, the gyroscopic effect of the wheel will resist any deviating movement about a horizontal axis 45 of the aircraft from the position for normal horizontal flight.

When the helicopter slot cover blades 27 are in the elevated position illustrated in Figs. 5 and 6, and the rotation of the wheel 50 being counter clockwise as illustrated in Fig. 4, the blades and the slots will have a helicopter action when rotating through the air, and will provide additional lift for the airplane.

Means are provided for adjusting the positions of the helicopter blade during rotation of the wheel, and such means may include a lug 36 depending from the lower surface of each blade 27, and each lug is pivotally connected with one end of an operating link 37 60 extending downwardly through the slot for the particular blade.

The lower end of each link 37 is pivotally connected with a sleeve 38 slidably keyed 65 on the shaft 30, and the sleeve 38 has rotatably

mounted thereon a collar 39 which is maintained stationary with respect to rotation, and may be carried at the upper ends of rods 40 and 40' which are mounted for vertically sliding in the bracket 34.

The lower ends of the rods 40 and 40' are provided with a slot and pivot connection with the outer end of an operating crank 41 mounted on a pivot 42 within the airplane fuselage, and connected with a handle lever 75 43 which is preferably provided with ratchet means indicated generally at 44 for maintaining the handle lever and operating crank 41 in any desired position of adjustment.

Thus by rotary movement of the handle 80 lever 43 about the pivot 42, the operating crank 41 will raise and lower the rods 40 and 40', and will thus raise and lower the sleeve 38 and the blades 27 through the links 37, thereby permitting any degree of opening 85 for the helicopter blades 27, and permitting any desired amount of air to be diverted downwardly through the slots 26.

I claim:

1. A stabilizer for aircraft and the like 90 including a gyroscope wheel comprising top and bottom conical walls having their bases abutting in the central plane of the wheel, and walls of the wheel forming angled radially extending helicopter slots.

2. A stabilizer for aircraft and the like, including a gyroscope wheel comprising top and bottom conical walls having their bases abutting in the central plane of the wheel, and walls of the wheel forming angled radially extending helicopter slots, and an adjustable closure member for each slot.

3. A stabilizer for aircraft and the like, including a gyroscope wheel comprising top and bottom conical walls having their bases abutting in the central plane of the wheel, walls of the wheel forming angled radially extending helicopter slots, and a helicopter blade mounted upon the wheel adjacent each slot.

4. A stabilizer for aircraft and the like, including a gyroscope wheel comprising top and bottom conical walls having their bases abutting in the central plane of the wheel, walls of the wheel forming angled radially extending helicopter slots, and a helicopter blade hinged upon the wheel adjacent each slot and adapted to close the slot.

5. A stabilizer for aircraft and the like, including a gyroscope wheel comprising top and bottom conical walls having their bases abutting in the central plane of the wheel, walls of the wheel forming angled radially extending helicopter slots, and a helicopter blade hinged upon the wheel adjacent each slot, and means for manipulating the blades for opening and closing the respective slots.

In testimony that I claim the above, I have hereunto subscribed my name.

NORMAN CLARK.
